[57] CLAIM

The ornamental design for aquatic vehicle, as shown and described.

DESCRIPTION

FIG. 1 is a front perspective view of an aquatic vehicle showing my new design, wherein the broken lines depict the aft end of a motor boat for environmental purposes only and from no part of the claimed design;
FIG. 2 is a left side elevational view thereof;
FIG. 3 is a right side elevation view thereof;
FIG. 4 is a front elevational view thereof;
FIG. 5 is a rear elevational view thereof;
FIG. 6 is a top plan view thereof; and,
FIG. 7 is a bottom plan view thereof.
